UNITED STATES PATENT OFFICE.

EDWARD OSCAR DAMEN, OF CINCINNATI, OHIO.

DESIGN FOR A SHAVING-STAND.

No. 40,059.

Specification for Design.

Patented June 15, 1909.

Application filed March 6, 1909. Serial No. 481,857. Term of patent 7 years.

To all whom it may concern:

Be it known that I, EDWARD OSCAR DAMEN, a citizen of the United States, residing at Cincinnati, in the county of Hamilton and State of Ohio, have invented a new, original, and ornamental Design for a Shaving-Stand, of which the following is a specification, reference being had to the accompanying drawing, forming a part thereof.

The figure is a perspective view of my new shaving stand.

What I claim is:

The ornamental design for a shaving stand as shown in the accompanying drawing.

EDWARD OSCAR DAMEN.
